UNITED STATES PATENT OFFICE.

GEORGE MARSH, OF NASHVILLE, TENNESSEE.

THONG-CUTTER.

SPECIFICATION forming part of Letters Patent No. 375,372, dated December 27, 1887.

Application filed September 8, 1887. Serial No. 249,505. (No model.)

To all whom it may concern:

Be it known that I, GEORGE MARSH, a citizen of the United States, residing at Nashville, in the county of Davidson and State of Tennessee, have invented certain new and useful Improvements in Thong-Cutters; and I do hereby declare the following to be a full, clear, and exact description of the invention, such as will enable others skilled in the art to which it appertains to make and use the same.

My invention is an improvement in hand cutting-stamps for making leather thongs or strings; and it consists in certain details of construction and arrangement of the parts composing a thong-cutting implement when constructed according to my invention, whereby the blade is held secure in place or may be removed for sharpening or adjusted to cut wide or narrow strips, as and for the purposes as will be hereinafter more fully described, and pointed out in the claims.

The object of my invention is to form a convenient implement or cutting-stamp for use of harness-makers, shoe-makers, and others, whereby leather thongs or strings of different lengths and widths may be formed by a single blow, and to accomplish which I proceed as follows, reference now being had to the accompanying drawings for a better understanding of the details of construction and arrangement of the several parts composing a thong-cutter when constructed according to my invention, and in which drawings—

Figures 1 and 2 represent views in elevation of a thong-cutter constructed according to my invention; Fig. 3, a central transverse sectional elevation of a portion of the lower end of the same, and Fig. 4 a bottom view. Fig. 5 is a similar view to Fig. 3, showing the clamping-band as with an inwardly-projecting flange for engaging over the edge of the last round of the cutter shown in Fig. 6.

A is the handle or body proper of the implement, made of a heavy stout piece of wood and with a leather cushion, *a*, at its top end to receive the impact of the blow when using the implement and prevent injury to the end thereof, and a central projection, *a'*, at its bottom, upon which to receive and hold the cutter, as will presently appear. Around the lower end of the handle A is a band, B, for

clamping the cutter-blade in position upon the handle.

K is the cutter blade or knife, which is made of a single strip of thin spring-steel—such as a 55 clock-spring—having one edge sharpened, and with a slot or similar means, as at *k*, receiving a stud, *a*², on the projection *a'* of the handle, whereby the cutter is held in place.

P is a continuous narrow strip of leather interposed between the convolutions of the cutter-blade to separate said convolutions the desired distance apart. At the back of the cutter a cushion, *b*, may also be arranged to prevent injury to said cutter and handle. 60

As before stated, the cutter is a thin strip of spring-steel, so that strips of leather of different thicknesses may be interposed between the same and the distance apart of said convolutions increased or diminished, whereby thongs 65 of different width is the result.

When arranging the implement for use, the cutter is first attached to the central projection, *a'*, of the handle. A narrow strip of leather of the desired thickness the thong is 75 to be is now placed adjacent the cutter-blade and the two curled or wound tight around the said projection of the handle, and then held secure in place by the clamping-band B, which band may be slotted with set-screw, as in Fig. 80 1, or with ears, as in Fig. 2, to facilitate the adjustment thereof. The instrument is now placed upon the piece of leather from which the thong is to be cut, when, upon a sharp blow being directed upon the top end of the 85 handle, the cutter is forced through the leather and divides the same into a narrow strip or "thong," as it is called.

By having the cutter detachable, in addition to that of permitting different widths of thongs 90 to be made, the same may be more readily sharpened than were the knife rigid in its handle. To cut long thongs a long cutter is to be employed and the number of convolutions thereof proportionally increased. If desired, 95 the outer end of the cutter-blade, sufficient, say, to make about one revolution of the cutter when curled up, may be formed with a narrow portion, as shown in Fig. 6, to engage an inwardly-projecting flange on the band, as 100 shown in Fig. 5.

I am aware that a helical cutting-die is not

broadly new. This, therefore, I do not claim; but

What I do claim as new and of my invention is as follows, viz:

- 5 1. In a thong-cutter, the combination, with the handle formed with a central projection to receive the first coil of the cutter-blade, of said thin spring-steel cutter-blade wound upon said projection of the handle, continuous strip of leather interposed between the convolutions of the blade, and a clamping-band for holding the parts together.
- 10 2. The combination, in the thong-cutter herein described, with a handle having a central projection, of a helical cutter-blade formed of a narrow ribbon of spring-steel, with means at its inner end to engage said projection of the handle, means for separating the convolutions of the cutter-blade, and means for securing the whole to the handle.
- 15
- 20

3. In a thong-cutter, in combination with the handle, helical cutter, and interposed continuous strip of leather, the clamping-band for securing the cutter in position.

4. In a thong-cutter, in combination with 25 the handle and helical cutter-blade formed with a narrow portion at one end, the clamping-band having an inwardly-projecting flange along its lower edge, for the purposes specified.

5. In a thong-cutter, in combination with 30 the handle formed with a central projection to receive the cutter-blade and bearing a stud, the knife with slot at one end and a narrow portion at the other, and clamping-band with inwardly-projecting flange at its lower edge. 35

GEORGE MARSH.

In presence of--
EWING THOMPSON,
WALTER MCKAY.
